AIR PRESSURE RELIEF MEANS FOR ROTARY CUTTERS

Harold E. Krueger, Saginaw, Mich., assignor to Mitts and Merrill, Saginaw, Mich., a corporation of Michigan

Application January 14, 1952, Serial No. 266,390

5 Claims. (Cl. 164—60)

This invention relates to means for relieving the air pressure normally built up ahead of the blades of a rotary cutter or shredder experienced particularly when the rotating blades are enclosed within a closely confining housing.

In rotary cutters such as those used for paper shredding and size reduction of plastic materials, the blades are mounted on a fly wheel of substantial diameter and rotated at high speeds. These blades are normally mounted on one face of a heavy fly wheel and together with the fly wheel act as air impellers, forcing a mass of air ahead of each blade. In this manner, appreciable air pressures are built up ahead of the blades, which air pressures are relieved as the blades pass the material feeding inlet by the air escaping through this inlet. This escaping air causes serious difficulty in the feeding of the material, resulting in fluttering and rolling back of the material being fed to the machine. This is particularly true in the case of paper shredders where the material is normally thin and has a substantial air foil surface to cause it to roll back upon itself. Various means have heretofore been devised to correct this condition but until the present invention these means have failed to correct this condition.

Accordingly, the present invention is designed to eliminate the air pressure ahead of the cutting blade before the cutting blade reaches the material inlet opening. By thus relieving this air pressure, there will be no appreciable exhausting of air through the material inlet. Thus, the material may be fed through the inlet at a predetermined rate and without interference. It is a further object of my invention to correct this air pressure condition known to the trade as "blowout" by means which are both simple and dependable. An additional object of my invention is to increase the capacity of rotary cutters. A further additional object of my invention is to provide a relief for this blowout condition through means which are adaptable not only to new machines but also may be readily applied to existing structures without costly modification.

These and other objects and advantages of my invention will be apparent to those skilled in the design and use of rotary cutting equipment upon reading the following specification and the accompanying drawings.

In the drawings:

Figure 1 is a front, elevation view of my invention taken along the plane I—I of Figure 2.

Figure 2 is a side, elevation view of my invention.

Figure 3 is a sectional, elevation view of my invention taken along the plane III—III of Figure 1.

Figure 4 is a sectional, elevation view of my invention taken along the plane IV—IV of Figure 3 but showing only the rotor and cutter blades.

Figure 5 is a fragmentary, sectional, elevation view of my invention using a plate to form the air escape passageway.

Figure 6 is a fragmentary, front, elevation view of a modified construction for my invention.

In the following description the terms "inwardly" and "outwardly" are frequently used and are to be taken to mean "inwardly" toward the geometric center of the machine and "outwardly" away therefrom.

In the following description, for the purpose of brevity and clarity, I describe my invention as applied to a paper shredder. The selection of this particular equipment as a vehicle for describing my invention is not to be considered as a limitation as it is apparent that my invention

2

may be applied to any machine having blades mounted upon a rotating disc or fly wheel such as plastic size reducers and numerous other types of equipment used in various industrial and agricultural fields.

Referring now to the drawings in greater detail, the numeral 1 refers to a circular housing mounted on legs 2. Within the housing is a rotor 3 supported by the shaft 4. The shaft 4 is journaled to the housing 1 by means of the bearings 5 and on one end has a pulley 6 for receiving power from any suitable source such as a prime mover.

Mounted on the forward face of the rotor 3 are detachable cutting or shearing blades 7. These blades may be plain or serrated and either straight or arcuate depending upon the material to be reduced. The blades 7 are securely held to the rotor by the screws 8. The rotor is shown equipped with 4 blades, but a greater or lesser number of blades may be used depending, in part, upon the material to be cut in the machine. The blades 7 shear or cut the material against a cooperating cutting block 9 mounted to the inside wall of the housing 1. The upper surface of the cutting block constitutes an extended radius of the shaft 4 and, preferably, is horizontal.

In the same plane as the shearing block 9 is a feeding trough 10 communicating with the interior of the housing 1 through the slotted aperture 11. The lower wall of the aperture 11 and the floor of the feeding trough 10 are both flush with the top surface of the shearing block 9. The outer end of the feeding trough 10 is supported by a leg 12. The feeding trough 10 is illustrated only as a rectangular chute through which material can be fed into the machine. It will be recognized that numerous other types of feeding devices may be used such as a platform with cooperating feed rolls or a live floored conveyor. The material cut in the machine is discharged through the venting tube 13.

The above paragraphs describe one type of conventional structure for a paper shredder to which my invention may be applied. In the area immediately above the aperture 11, the forward face of the housing 1 is formed into an outwardly projecting bubble 20 defining a chamber communicating with the interior of the housing. The chamber, in vertical cross-section, preferably has a shape generally conforming to that of an airfoil with the greatest depth of the cavity adjacent the aperture 11. This bubble 20 internally provides an air passageway 21 open to the knife blades 7 and immediately above the shearing block 9. The bubble extends from adjacent the shaft 4 out to the periphery of the housing 1. The lower lip of the bubble extends inwardly of the plane of the inner surface of the front wall of the housing 1. For maximum performance this lip should be placed as close to the knife blades 7 as possible without incurring physical interference.

The bubble 20 may be formed in the front wall of the housing 1 or, it may be provided by making a cutout in this wall and covering the cutout with a suitably shaped plate 23 secured to the housing 1 by bolts 30 or other suitable fastening means (Figure 5). The use of the cutout and coverplate arrangement is particularly adapted to the modification of existing equipment.

My invention may be applied either to new or existing equipment in the shape of a segment of a circle rather than a rectangle (Figure 6). The lower extremity of the segmental bubble 24 is identical to the lower edge of the bubble 20 but the upper extremity is inclined upwardly from its point of intersection with the lower edge adjacent the inward edge of the trough 10. In cross-section, the segmental bubble 24 has the same general shape as the bubble 20.

The operation of my invention is simple. The rotor 3 is rotated in such a manner that the cutter blades 7 move downwardly to pass the cutter block 9. The rotor must be operated at a high enough speed to cause the cutter blades 7 to act as air impellers. The housing 1 closely confines the rotor 3 and cutter blades 7, preventing this air from escaping from ahead of these blades. It is desirable to design the housing 1 to closely confine these parts both to keep the size and weight of the machine at a minimum and to utilize the air pumped by the cutter blades to forcibly eject the cut or shredded material through the discharge tube 13.

In the operation of the machine, the air piles up under pressure ahead of each blade while at the same time there is a substantial decrease in the static pressure of the air behind each cutter blade. By means of my bubble 20, a by-pass or passageway 21 is created for this air between the front and back of the blades. Thus, as the blades approach the aperture 11, the air piled up ahead of each blade is permitted to flow back to the area of reduced static pressure behind that blade. The substantial differential in pressure between the front and back of the blades will induce the air to transit the passageway 21. Thus, when the blade reaches the aperture 11 there is little or no air under pressure travelling ahead of the blade to cause a blowout through the aperture 11. The extension of the lower lip of the bubble 20 inwardly of the inner surface of the housing 1 acts as a scoop to remove any remaining excess air from ahead of the blades immediately before they reach the aperture 11.

When the segmental bubble 24 is employed, the fact that the passageway created by the bubble is reduced to nothing immediately adjacent the shaft 4 does not affect the efficiency of my machine. The quantity of air piled up ahead of each blade becomes proportionately less as the shaft 4 is approached because of the decreased velocity of the blades 7 and the shorter path of travel as well as the fact that the air tends to move radially outwardly under the influence of the rotating blades.

It will be recognized that numerous other modifications of my invention may be made without departing from the principle thereof. Each of these modifications is to be considered as included in the hereinafter appended claims unless these claims by their language expressly state otherwise.

I claim:

1. In a housing for a rotary knife chamber, said housing including therein a material inlet opening in the face thereof, a rotor mounted within said housing, knife blades mounted radially upon said rotor, a cooperating stationary knife below the material inlet opening of said housing, a material outlet in the periphery of said housing and means to drive said rotor, the improvement comprising: an air flow control chamber; said air flow control chamber positioned rotationally ahead of and adjacent to said material inlet opening of the housing; said air flow control chamber extending outwardly from the plane of the face of the housing and extending radially from the center of the face of the housing to the periphery thereof, said chamber radii being of such length as to allow passage of air around a knife as the knife moves past said air flow control chamber.

2. In a housing for a rotary knife chamber, said housing including therein a material inlet opening in the face thereof, a rotor mounted within said housing, knife blades mounted radially upon said rotor, a cooperating stationary knife below the material inlet opening of said housing, a material outlet opening in the periphery of said housing and means to drive said rotor, the improvement comprising: an air flow control chamber extending outwardly from the plane of said housing; said air flow con-

trol chamber positioned rotationally ahead of and adjacent to said material inlet opening; the lower edge of said air flow control chamber being the upper edge of the material inlet opening; the said air flow control chamber substantially following a pair of radii extending outwardly along the face of said housing from the center of the face of the housing to the periphery thereof, said radii being of such length as to allow passage of air around the knife blade as the knife blade moves past the said air flow control chamber.

3. In a rotary cutting machine including a housing and a rotor rotatably mounted therein; knives mounted radially upon said rotor; a cutting block mounted to the inside surface of said housing for cooperation with said knives; an aperture through said housing immediately above said block, the improvement in said cutting machine comprising: a bubble in said housing extending along that edge of said aperture remote from said block and extending outwardly from the plane of said housing, said bubble defining an air passageway with respect to the interior of said housing and extending from the area ahead of to the area behind each of said knives as said knives approach said aperture.

4. In a rotary cutting machine including a housing and a rotor rotatably mounted therein; knives mounted radially upon said rotor; a cutting block mounted to said housing for cooperation with said knives; an aperture through said housing immediately above said block, the improvement in said cutting machine comprising: a bubble in said housing extending along that edge of said aperture remote from said block and extending outwardly from the plane of said housing, said bubble defining an air passageway with respect to the interior of said housing and extending from the area ahead of to the area behind each of said knives as said knives approach said aperture; the edge of said housing where said bubble adjoins said aperture extending into said housing.

5. In a rotary cutting machine including a housing and a rotor rotatably mounted therein; knives mounted radially upon said rotor; a cutting block mounted to said housing for cooperation with said knives; an aperture through said housing immediately above said block, the improvement in said cutting machine comprising: a bubble in said housing extending along that edge of said aperture remote from said block and extending outwardly from the plane of said housing, said bubble defining an air passageway with respect to the interior of said housing and extending from the area ahead of to the area behind each of said knives as said knives approach said aperture; the edge of said housing where said bubble adjoins said aperture extending into said housing to a point immediately adjacent to the plane of said knives.
